UNITED STATES PATENT OFFICE.

JOHN W. CONNORS, OF DEDHAM, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

Application filed September 29, 1927. Serial No. 222,879.

This invention relates to buttonhole sewing machines and particularly to a buttonhole cutting mechanism of the type adapted to cut a buttonhole slit with an eye at one 5 end.

In cutting a buttonhole slit of this type the buttonhole cutter cuts from the cloth or other piece of work a small cloth fragment at the place where the eye is formed and the 10 cutter is usually provided with a delivery passage into which this cloth fragment enters and through which it passes to the outside of the cutter. It sometimes happens, however, that the cloth fragment will not 15 remain in the passage when the cutter is raised but will adhere to the work in which case the fragment is liable to be sewed into the buttonhole thus producing imperfect work.

20 It has been proposed to avoid this difficulty by providing an ejector which is associated with the cutter block and which positively forces the cloth fragment as each buttonhole is cut into said delivery passage.

25 My present invention relates to improved means for actuating the ejector.

In order to give an understanding of the invention I have illustrated in the drawings a selected embodiment thereof which will 30 now be described after which the novel features will be pointed out in the appended claims.

Fig. 1 is a fragmentary sectional view of a portion of a buttonhole sewing machine 35 embodying my invention and showing the cutter raised;

Fig. 2 is a fragmentary view showing the operation of the ejector, the cutter block, and cutter being shown in section;

40 Fig. 3 is a section on substantially the line 3—3, Fig. 1;

Fig. 4 is a view similar to Fig. 2 showing a modification of the invention but illustrating the cutter block in side elevation;

45 Fig. 5 is a top plan view of Fig. 4;

Fig. 6 is a section on the line 6—6, Fig. 3.

Fig. 7 is an under side view of the cutter.

Inasmuch as the present invention relates 50 simply to the buttonhole cutter of a buttonhole sewing machine I have not thought it necessary to illustrate the complete machine herein but have shown only such parts of a buttonhole sewing machine as is necessary to enable my invention to be understood.

55 In the drawings 1 indicates portions of

the frame of a buttonhole sewing machine which carry the stitch-forming mechanism, the latter, however, not being herein shown as it forms no part of the present invention, although it might be stated that the stitch-forming mechanism comprises the usual upper needle and also under thread handling mechanism which is mounted on a turret indicated generally at 2 and carried by bearings 3 in the frame 1. During the sewing 60 around the eye of the buttonhole the stitch-forming mechanism including the turret 2 is given a partial rotation as usual in buttonhole sewing machines and such rotation is derived from a vertically-arranged oscillatory shaft 4 which is carried by the frame 1 and which is connected by suitable gearing with the turret and the needle bar carrier all as usual in buttonhole sewing machines and as will be readily understood by 65 those skilled in the art.

The buttonhole cutter which is of the usual construction is shown at 6 and it is carried by a cutter arm 7 that is pivoted to the frame 1 at 8. Co-operating with the cutter 6 is a cutter block 9 which is carried by a suitable supporting bracket 10 that is secured to the frame 1. The cutter is provided with the cutting edge 11 which cuts the slit of the buttonhole and which terminates at one end in an eye-forming portion 12 which cuts out the eye of the buttonhole. The buttonhole cutter 6 is provided with a delivery passage 16 leading upwardly from the eye-forming portion 12 and communicating with an outlet or discharge passage 17 formed in the arm 7, the discharge passage 17 opening through the side of the arm, all as usual in buttonhole cutters of this type.

The cutter arm 7 is given a rocking movement about its pivot 8 at the proper time in the sewing cycle thereby to bring the cutter 6 against the cutting block 9 and cut the buttonhole slit in the work 13 as will be readily understood by those skilled in 95 the art.

Associated with the cutter block 9 there is an ejector 14 in the form of a pin which operates vertically through said block and is situated in line with the eye-forming portion 12 of the buttonhole cutter.

Means are provided whereby while the cutter is in its cutting position against the block 9 the ejector will be raised as shown in Fig. 2 whereby the cloth fragment 15 which 100

110

is cut out in forming the eye of the button-hole will be forced up into the delivery passage 16 thereby clearing said fragment from the work and avoiding any possibility 5 that it will remain in the work when the cutter is raised and thereby become sewed into the buttonhole.

In my present invention I have provided for actuating the ejector 14 from the oscillatory shaft 4 by which the stitch-forming mechanism is given its rotary movement.

In Figs. 1, 2 and 3 I have shown one simple way in which this may be accomplished. The ejector 14 is secured to and 10 rises from a plunger 18 which operates in a recess formed in the bracket 10, said plunger having a head 19 at its lower end which is engaged by a spring 20 that 15 normally tends to hold the ejector in its depressed or inoperative position shown in 20 Fig. 1.

The plunger 18 has a pin 21 extending laterally therefrom and operating in a slot 22 formed in the supporting bracket 10, 25 said pin projecting beyond the supporting bracket. The projecting end of the pin is received in a slot 23 formed in the end of a lever 24 which is pivoted to the supporting bracket 10 at 25. Said lever is provided 30 at its end with a cam surface 26 which is adapted to be engaged by a projection 27 carried by a collar 28 that is fast on the shaft 4. As the shaft rotates the collar from the position shown in Fig. 35 1 to that shown in Fig. 2 the pin 27 will by its engagement with the cam face 26 depress the left hand end of the lever 24 thereby raising the right hand end and elevating the ejector 14 against the action of 40 the spring 20.

In some buttonhole sewing machines the buttonhole cutter is actuated when the machine is first started and before the stitch-forming mechanism is set in operation while 45 in other machines the buttonhole cutter is actuated after the stitch-forming operation has been completed. In either case there is commonly a turning movement of the shaft 4 at the time that the buttonhole cutter is 50 being operated; such turning movement operating to restore the stitch-forming mechanism to proper position for sewing the buttonhole, it being understood that the said stitch-forming mechanism has been turned 55 in sewing around the ends of the button-hole.

The turning movement which is thus given to the shaft 4 at the time that the button-hole is being cut operates the lever 24 60 through the pin 27 and cam face 26 thereby raising the ejector and this raising movement occurs while the cutter is in its cutting position against the cutter block as shown in Fig. 2. As a result of this operation the cloth fragment which is cut from

the work 13 by the eye-forming portion 12 of the cutter is forced positively into the passage 16 and is thus prevented from being retained by the work as the cutter rises.

In Figs. 4 and 5 I have shown a little different embodiment of the invention. In this embodiment the ejector is given its vertical movement by a sliding actuator 29 which is slidably mounted on the supporting 75 bracket 10 and is provided with a cam surface 30 adapted to engage the pin 21 as the slide is moved from full to dotted line position Fig. 5. The slide is provided with a guiding slot 33 which receives a guiding 80 stud 35 carried by the bracket 10 and the slide is acted on by a spring 34 which normally tends to hold it in its rearward position shown in Fig. 4. The operative movement of the slide from the full to the dotted 85 line position Fig. 5 is secured by a cam member 31 mounted on the shaft 4. This member 31 is provided with a shoulder 32 situated to engage the end of the slide 29 as the shaft 4 is turned. During the cutting of the buttonhole the shaft 4 will turn from the full to the dotted line position Fig. 5 and will subsequently have a reverse turning movement to restore the stitch-forming 90 mechanism to normal position, and during its rotation from the full to the dotted line position the slide 29 is actuated to raise the ejector into the position shown in Fig. 2, this movement occurring while the cutter is 95 in its cutting position against the cutter block 9.

It will be observed that by means of my invention the ejector is actuated directly by the shaft 4 and the construction is simple and one involving relatively few parts.

I claim:

1. In a buttonhole sewing machine having a cutting block, a buttonhole cutter co-operating therewith and provided with an eye-forming portion and a delivery passage leading from said eye-forming portion, an oscillatory shaft by which the stitch-forming mechanism is given a turning movement, the combination with said cutter, cutting block and shaft, of an ejector operating 110 through the block for forcing into said passage the cloth fragment cut out by the eye-forming portion of the cutter, and means on said shaft to actuate said ejector as the shaft turns.

2. In a buttonhole sewing machine having a cutting block, a buttonhole cutter co-operating therewith and provided with an eye-forming portion and a delivery passage 115 leading from said eye-forming portion, an oscillatory shaft by which the stitch-forming mechanism is given a turning movement at the ends of the buttonhole, the combination with said cutter, cutting block and shaft, of an ejector operating through the 120

block for forcing into said passage the cloth fragment cut out by the eye-forming portion of the cutter, an ejector actuator, and ejector-operating means actuated directly from said shaft.

3. In a buttonhole sewing machine having a cutting block, a buttonhole cutter co-operating therewith and provided with an eye-forming portion and a delivery passage leading from said eye-forming portion, an oscillatory shaft by which the stitch-forming mechanism is given a turning movement,

the combination with said cutter, cutting block and shaft, of an ejector operating through the block for forcing into said passage the cloth fragment cut out by the eye-forming portion of the cutter, an ejector actuator, and a projection on said shaft for giving operative movement to said actuator as the shaft turns.

In testimony whereof, I have signed my name to this specification.

JOHN W. CONNORS.
